(57) CLAIM

The ornamental design for the boot, as shown and described.

DESCRIPTION

FIG. 1 is an isometric view of a boot showing our new design.

FIG. 2 is a front elevational view thereof.

FIG. 3 is a rear elevational view thereof.

FIG. 4 is a right-side elevational view thereof.

FIG. 5 is a left-side elevational view thereof.

FIG. 6 is a top plan view thereof; and,

FIG. 7 is a bottom plan view thereof.

Any broken lines, colors, and/or patterns in the drawings are for illustrative purposes only and form no part of the claimed design.

The broken lines in the drawings represent portions of the boot that form no part of the claim.
